UNITED STATES PATENT OFFICE.

THOMAS J. DAWSON, OF COLUMBIA, MISSOURI.

LAP-RING.

1,314,637.

Specification of Letters Patent. Patented Sept. 2, 1919.

Application filed January 27, 1919. Serial No. 273,460.

To all whom it may concern:

Be it known that I, THOMAS J. DAWSON, a citizen of the United States, residing at Columbia, in the county of Boone and State 5 of Missouri, have invented certain new and useful Improvements in Lap-Rings, of which the following is a specification, reference being had to the accompanying drawings.

10 This invention relates to certain improvements in lap rings, and it is an object of the invention to provide a novel and improved device of this general character comprising two members pivotally connected one relative to the other, and whereby each of said members has limited movement independently of the pivotal connection, so that said members when in working or overlapping relation will readily adjust or compensate 15 themselves to the part or parts to which said members are engaged in the event such part or parts should be uneven or unduly worn so that the possibility of breaking the connecting or pivotal member is substantially 20 entirely eliminated.

The invention consists in the details of construction and in the combination and arrangement of the several parts of my improved lap ring whereby certain important 30 advantages are attained and the device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:

40 Figure 1 is a view in elevation of a lap ring constructed in accordance with an embodiment of my invention, a second position of one of the members being indicated by dotted lines;

45 Fig. 2 is a view in elevation of one of the members of my improved lap ring as herein included;

50 Fig. 3 is a view in elevation of the second member of the lap ring as herein disclosed; and

Fig. 4 is a sectional view taken substantially on the line 4—4 of Fig. 1.

As disclosed in the accompanying drawings, my improved lap ring comprises two 55 substantially duplicate members A and B, which, when in assembled relation are re-

versely disposed. Each of the members A and B is substantially E shaped in form, and one of said members, as A, at the heel or connecting portion between an end member 1 and the central or body portion 2 is provided with an opening or slot 3 angularly disposed relative to the longitudinal axis of the central or body portion 2 and preferably on an angle of substantially 45°. 60 The outer end portion or extremity of the end member 1 of the member B which contacts with the end member 1 of the member A just referred to is provided with a slot 4 also angularly disposed and which registers with the opening 3 when the members A and B are in overlying and working relation.

Loosely disposed through the openings 3 and 4 is a pivotal member 5 such as a rivet 75 having its opposite end portions offset and which rivet is of a diameter less than the length of said openings 3 and 4 so that the members A and B are capable of limited movement one relatively to the other independently of their pivotal connection, so that the device may be applied or removed with greater facility, and further to afford means whereby said members A and B when in working or applied position compensate for 80 any irregularities of the part or parts with which the members A and B are engaged without imposing undue strain upon the pivotal member 5 which would otherwise result in the fracture or other injury to said 90 member 5.

The central arms 6 of the members A and B, when said members are in overlapping or working relation closely approach each other as is clearly indicated in the accompanying 95 drawings, and which arms 6 afford effective means whereby an unhooking or uncoupling is prevented, particularly in the event when slack of motion or draft occurs, so that my improved lap ring is particularly adapted 100 for use in connection with draft appliances particularly of a type used in connection with farming.

It is to be particularly noted in Fig. 4 that the walls of the slots 3 and 4 are chamfered or oppositely beveled toward the center thereof, in order to facilitate the relative movements of the members A and B.

From the foregoing description, it is thought to be obvious that a lap ring constructed in accordance with my invention is particularly well adapted for use by reason 110

of the convenience and facility with which it may be assembled and operated, and it will also be obvious that my invention is susceptible of some change and modification 5 without departing from the principles and spirit thereof, and for this reason I do not wish to be understood as limiting myself to the precise arrangement and formation of the several parts herein shown in carrying 10 out my invention in practice except as hereinafter claimed.

I claim.

1. As a new article of manufacture, a lap ring comprising two substantially duplicate members reversely arranged, each of said members including inwardly disposed end arms, one of said members at its junction with an end arm being provided with a slot inclined relative to the longitudinal axis of 20 the member, and an end arm of the second member having in its free end portion a slot adapted to completely register with the slot of the first named member when the members are in overlapping relation, and a 25 pivotal member loosely disposed through said slots, said member being of a diameter less than each of the slots, so that said first named members and rivet have relative movement lengthwise of the slots.
- 30 2. As a new article of manufacture, a lap ring comprising two substantially duplicate members reversely arranged, each of said members including inwardly disposed end arms, one of said members at its junction with an end arm being provided with a slot 35 inclined relative to the longitudinal axis of the member, and an end arm of the second

member having in its free end portion a slot adapted to completely register with the slot of the first named member when the 40 members are in overlapping relation, and a pivotal member loosely disposed through said slots, said member being of a diameter less than each of the slots, so that said first named members and rivet have relative 45 movement lengthwise of the slots, each of said first named members being provided with an inwardly directed central arm.

3. As a new article of manufacture, a lap ring comprising two substantially duplicate 50 members reversely arranged, each of said members including inwardly disposed end arms, one of said members at its junction with an end arm being provided with a slot inclined relative to the longitudinal axis of 55 the member, and an end arm of the second member having in its free end portion a slot adapted to completely register with the slot of the first named member when the members are in overlapping relation, and a 60 pivotal member loosely disposed through said slots, said member being of a diameter less than each of the slots, so that said first named members and rivet have relative 65 movement lengthwise of the slots, the walls of the slots of the first named members being chamfered.

In testimony whereof I hereunto affix my signature in the presence of two witnesses.

THOMAS J. DAWSON.
